FUEL CONTROL FOR HOT-AIR HEATERS

Ralph W. De Lancey, Meriden, Conn., assignor to
 The Miller Company, Meriden, Conn., a corpora-
 tion of Connecticut

Application November 13, 1943, Serial No. 510,183

19 Claims. (Cl. 126—110)

1

The present invention relates to fuel control valves for liquid fuel burners, and is more particularly directed toward combined constant level and metering valves for gravity fed liquid fuel burners.

The present invention contemplates a metering valve in which the valve stem when free of restraint is biased toward open position, and wherein a manually operable device, such as a lever, may be moved against spring tension from a position where it overpowers the valve stem biasing means and forces the valve to closed position to a burner operating position where it releases the valve stem for movement toward open position. A high fire stop is provided to limit the movement of the valve stem toward open position. The manually operable device is preferably latched in running or operating position against spring pressure so that when released the valve stem is forced to closed position.

The release of this latch may be employed in the routine operation of shutting down the burner. The limiting of the opening of the metering valve to amounts less than the maximum may, if desired, be accomplished by mechanism such as shown and claimed in my U. S. Patent No. 2,428,867, dated October 14, 1947.

The present invention also contemplates the provision of thermal responsive means close to the burner and preferably in the path of the forced draft for the burner which acts on excessively high temperature to release the latch and therefore shut down burner operation.

The level of the liquid in the constant level valve chamber may be controlled by any suitable form of liquid level responsive mechanism. Where such valves are employed in portable devices there is a tendency for the liquid level responsive mechanism to move about, whether liquid is in the chamber or not and the inlet valve is subject to wear and the likelihood of being opened when no fuel is wanted, thereby causing leakage. To overcome these difficulties the present invention contemplates means for insuring the closing of the inlet valve and the holding of the float or liquid level mechanism stationary at all times when the metering valve is closed.

While the float valve control and the metering valve control to be described herein may be used separately or in combination with common parts, they are also suitable for use with the thermal control to effect a simultaneous closure of both valve controls. A portable warm air heating furnace, wherein these parts are

2

especially suitable for use, is shown in my application, Serial No. 510,181 filed November 13, 1943.

Other and further objects will hereinafter appear as the description proceeds.

5 The accompanying drawings show, for purposes of illustrating the present invention, an embodiment in which the invention may take form, it being understood that the drawings are 10 illustrative of the invention rather than limiting the same.

In these drawings:

Figure 1 is a rear elevational view of a portable hot air heating furnace to which the controls (shown in running position in full lines and in shut-off position in dot-and-dash lines) are applied, the fuel burner and combustion chamber being in section on the line 1—1 of Figures 3 and 4;

20 Figure 2 is an enlarged elevational view of the burner and valve controls also taken from the rear of the furnace and showing the starting control in running position and the thermal control in various positions of adjustment;

25 Figure 3 is a horizontal sectional view on the line 3—3 of Figure 2;

Figure 4 is a vertical sectional view on the line 4—4 of Figures 1, 2 and 3, the float and metering valves being shown open;

30 Figure 5 is a fragmentary vertical sectional view on the line 5—5 of Figure 3;

Figure 6 is an enlarged vertical sectional view on the line 6—6 of Figure 3 showing the metering valve closed;

35 Figure 7 is a fragmentary view similar to Figure 6 showing the metering valve open;

Figure 8 is an elevational view of the valve operating mechanisms in the open or running position and taken in the direction of the arrow

40 8 in Figures 1, 2, 3, and 6; and

Figure 9 is an elevational view of the operating mechanism taken from the right of Figure 8.

The bottom housing unit A of the portable hot air heating furnace has a semi-cylindrical bottom housing member 20, to which is welded a tubular burner housing 21. This burner housing extends below the bottom housing member 20 as indicated at 21a (Figure 1) and above it as indicated at 21b. The unit A also has legs 50 22 for support.

The combustion drum C has an outer cylindrical body 24, and end walls 25 and 26. These end walls have aligned openings 27, which receive air tubes 28. The bottom part of the drum body 24 is provided with an opening 29 in which

is welded a downwardly extending fire tube 30 near one end of the combustion drum and concentric with tube 21. The adjacent wall 25 of the combustion chamber supports an inverted box-like baffle 31 which protects the adjacent ends of the air tubes 28 from direct impingement of the flame and yet permits the heat to pass out about these air tubes. The combustion drum is provided with a stack opening 32 at the top and at the end opposite the fire tube 30. The upper edge of the tube 21 engages the lower surface of the drum 24 in the side away from the end wall 25 so as to provide an opening 37 for supplying air to the burner B. A short tube 38 is welded into the stack opening 32.

The top housing unit D has a semi-cylindrical top housing member 40, similar to the bottom housing member 20, but provided with an opening 41 over the stack tube 38 discharging into a stack 44. The top housing member 40 fits over the top of the combustion drum and the top and bottom housing members are secured together in any suitable manner. The housing accommodates a blower whose fan is indicated at M and this blower acts to force air through the space between the combustion drum and housing and the tubes 28, as well as air for combustion through opening 37.

A cap F for the stack fits on the outer end of the stack and may either be placed in the stack or hung free by means of the chain 45 shown. When the cap is in the position indicated the products of combustion pass out through the stack, but when it is placed on the end of the stack the products of combustion do not pass out through the stack. In order to permit the products of combustion to escape from the drum without going up the stack, the end wall 26 of the drum is provided with flanged opening 46 adapted to receive and support a reversible plug G. When the plug is in the position shown it compels the products of combustion to go up through the open stack. When, however, the plug G is withdrawn, reversed end for end and reinserted the products of combustion may pass through the hole 48' in the stamping 48 and enter the plug. The air delivery cover H shown herein is one adapted to receive a duct, usually of fabric, for conducting air to the region to be heated. It serves to receive the air blown through the combustion drum and the space between the combustion drum and the housing, as well as the contaminated air when the plug G and the cap F are in proper position for delivering contaminated air.

The fuel supply tank I delivers fuel to the strainer J through pipes, one of which is shown at 62. The discharge pipe from the strainer is indicated at 66 and it leads into the fuel control valve formed in part of the burner control valve unit B.

The body casting of the burner valve control unit B is designated by the reference character 70. It has a float chamber 71 which is closed off by a cover 72, fastened in place by screws 72'. The cover has a rearwardly extending tubular coupling element 73 for coupling to the fuel line 66. A valve seat member 74 is threaded up into a drilling 74' in the cover member 72 and this valve seat member 74 receives a valve pin 75 which is normally controlled by a float 76 hinged at 77. When the parts are in the position shown in Figure 6 the float 76 and float control valve 75 operate similarly to the float valve in an automobile engine carburetor and maintain a prede-

termined supply of fuel in the float chamber 71. The casting 70 is provided with an outlet valve seat insert 78 at the bottom of the float chamber, which cooperates with a metering valve stem 79 urged upwardly by a spring 80 and downwardly by mechanisms to be described. This valve forms the metering valve for the burner.

The constant level valve and metering valve are under manual control for the purpose of starting and stopping the burner and are under automatic control for the purpose of emergency shutdown of the burner as well as for the continuous control of the metering valve for normal continuous operation. These controls will now be described.

15 The starting lever for opening the fuel line into the fuel chamber 71 is shown at 81. It is pivoted at 82 to the U-shaped stamping 82' carried by the cover member and has a generally horizontally extending arm 83, which overlies the top of the cover member 72. When it is in the position shown in Figures 1, 2, 3, 4, 7, 8 and 9, the inner end of this arm 83 is latched in this position by a lever 84 pivoted at 85 to the stamping 82' and having a rear extension 86.

20 25 30 35 40 When the starting lever 81 is latched in this normal operating position, the arm 83 presses down on a pin 87 which extends through the float chamber cover 72 and normally rests on the top of a leaf spring 88. This leaf spring is carried by the under side of the cover 72 and is normally urged upwardly. It is arranged as shown in Figure 4 to be free of the float mechanism when in that position, but when the starting lever 81 is in the shut off position, as indicated in dot-and-dash lines in Figure 1 and in full lines in Figure 6, the pressure on the leaf spring 88 is removed and this spring is able to act on the float mechanism, so as to move it into the position to move the valve 75 to closed position and at the same time it will lock the float mechanism against vibration during shipment or transportation of the burner.

45 50 55 60 65 The starting lever 81 has a cam 89 adapted to act on a lever 90 pivoted to the stamping 82' at 91 and urged downwardly by a coiled spring 92. The lever 90 carries a leaf spring 93 whose position can be adjusted by high fire adjustment screw 94. The free end of the spring 93 extends above shoulder 95 on the valve stem 79 and is out of contact with this shoulder when the parts are in starting position. The spring 93, however, limits the height to which the metering valve stem may be moved by the coiled spring 80.

70 75 80 85 90 As there is the hazard of blower failure, or of choking off of the draft by simultaneously closing the stack and the delivery end of the combustion chamber, or by the stoppage of delivery of contaminated air from the furnace, there is the possibility of continuation of burner operation without proper draft which would bring about overheating near the burner and sooting of passages. To avoid such operation the furnace is provided with a bimetallic safety device N having a resilient bimetallic thermostat 96 supported from a bracket 97 in the space between tubes 21 and 30 and having an extension 98 engaging notched element 99 on the rear of latch lever 84. The bracket 97 is part of a plate 100 held in place on tube 30 by screws 100'. A shaft 101 threaded into bushing 102 is provided with a yoke 103 to receive the bimetallic member 96 and a handle 104 by which the thermostat may be adjusted to respond to dangerous temperature rises above varying ambient temperatures—such as -45° F.

or room temperature. Suitable stops 100a and 100b limit the movement of handle 104. On overheating the thermostat 86 expands and releases the starting lever 81 causing the float valve and metering valve to close.

When the starting lever 81 is shifted to open the valves and the furnace is cold, the metering valve will open to an extent determined by the air temperature control unit L in a manner to be described below. The fuel will then be allowed to flow through the metering valve at a predetermined rate which is the proper rate (more than pilot and less than maximum fire) for starting the burner. The fuel will pass down a sloping passage 106, see Figure 1, and enter the vaporizer 106, forming the other end of the body 70 of the burner unit B. The burner construction which forms the subject matter of concurrently filed application Serial No. 510,182, now Patent No. 2,432,143, issued December 9, 1947, will now be briefly described.

The vaporizer 106 has a central air tube 107 and a row of downwardly and inwardly extending air holes or drillings 108. The vaporizer carries a perforated sleeve 109, preferably having larger holes at the top than at the bottom and this sleeve is clamped in position by a ring 110 and bolts 111. The ring 110 is just the proper size to fit into the fire tube 30 and this tube is provided with a bead 112 to provide a stop for the ring. The ring is provided with perforations 113, shown more clearly in Figure 3, and carries upwardly extending rods 114 which support a flame spreading plate 115. The ring 110 also carries a downwardly and outwardly flaring skirt 116 which terminates just above the top of the vaporizer 106. The skirt compels the air to pass underneath it to where air is preheated. This skirt also acts to prevent flame from passing out through the sleeve 109 and up the tube 21. The bottom of the vaporizer 106 is covered by the cup shaped stamping 117 to provide an air space 118 and facilitate maintaining the vaporizer at a high temperature.

The unit B for the burner and fuel valve assembly is supported from the tube 21 by screws 119-119 which pass through holes in the tubes 21 and 30 and are threaded into ring 110 and by screws 120 which pass through holes in a bracket 121 welded to tube 21 and are threaded into the casting 70.

The bottom of the down draft tube 21 is closed off by a hemispherical stamping 122, which fits into the ring 123 carried by the bottom of the tube 21 and it is removably held in place by screws 124 threaded into ring 123. The casting 70 has a constriction as indicated at 125 which impedes the flow of heat lengthwise of the body member 70. As shown more clearly in Figure 1, the riser or air tube 107 receives a ring 126 which carries a number of fingers 127 of heat resistance wire of good thermal conducting material. These fingers extend up into the combustion space and carry heat down into the bottom of the vaporizer. A lighting tube 130 is carried on the front side of the furnace and extends through down draft tube 21 and the fire tube 30.

A reciprocating rod or slider 149 is operated upon by an air temperature responsive thermostatic apparatus 141 shown more fully in the applications above referred to, but for present purposes it is believed sufficient to say that when the apparatus is cold the bracket member 151 carried by slider 149 is brought to a position where it limits the opening of the metering valve stem to

an amount less than that allowed by the high fire stop 84. As the thermal apparatus is heated it first allows the metering valve to open for maximum fire and then as heating continues proceeds to cut down the fire to a low flame. As the furnace cools the firing rate is raised. The intensity of the fire, therefore, varies between the maximum and minimum, so that there is no likelihood of overheating the parts, or delivering the air at too high a temperature, or of extinguishment of the flame.

It will thus be seen that when the structure is cold or at ordinary room temperatures the extent of opening of the metering valve will be controlled by the adjustment of the stop mechanism for the air temperature responsive thermostat, and that when the starting lever 81 is moved to the starting position the fuel line will be opened to the float chamber, and fuel at a predetermined flow rate will pass down to the burner. This fuel will form a pool in the burner and must be immediately lighted. If for any reason the metering valve is allowed to remain open too long before the torch is supplied, the oil can flow from the vaporizer out through the tube 107 and escape through a drain hole 122' in the stamping 122. The lighting can be done by inserting a torch through the lighting tube 130. The fuel will be consumed in the burner and the natural draft caused by the combustion of the fuel will cause the products of combustion to pass up through the combustion drum, and air will be drawn in through the down draft tube 21. When the burner has been heated by natural draft sufficient to permit forced draft operation, the motor or engine may be started so as to operate the fan and blow air through the furnace and through the burner.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. In combination, a gravity fed liquid fuel burner, a flue above the burner for products of combustion, a down draft tube about the flue for supplying air to the burner, a fuel chamber above the level of the burner and disposed laterally of the down draft tube, an outlet valve in the fuel chamber, means biasing the outlet valve toward open position, a fuel passage between the outlet valve and burner, an inlet valve for the chamber, liquid level responsive mechanism for controlling the inlet valve, a spring actuated outlet valve closer, a spring actuated inlet valve closer, means for latching the valve closers in inactive position, and a thermostatic element in the down draft tube effective on reaching a predetermined temperature to release the latching means whereby both valves are closed.

2. In combination, a gravity fed liquid fuel burner, a flue above the burner for products of combustion, a down draft tube about the flue for supplying air to the burner, a fuel chamber above the level of the burner and disposed laterally of the down draft tube, an outlet valve in the fuel chamber having an upwardly projecting valve stem and a spring urging the valve stem upwardly, a fuel passage between the outlet valve and the burner, an inlet valve for the chamber, liquid level responsive mechanism for controlling the inlet valve, a spring actuated lever engageable

with the outlet valve stem for closing the valve, a spring actuated float lifter for closing the inlet valve, a manually movable member for disengaging the lever from the valve stem and the float lifter from the float whereby they are free to move, a latch for securing the manually movable member in said disengaged position, and a thermostatic element in the down draft tube effective on reaching a predetermined temperature to release the latch whereby both valves are closed.

3. In combination, a gravity fed liquid fuel burner, a fuel chamber disposed above and to one side of the burner and connected to it by a fuel passage, a metering valve in the fuel passage and having an upwardly urged valve stem, a cover for the chamber through which the valve stem protrudes, a float operated inlet valve for controlling flow of liquid into the chamber, a cover supported element spring biased to move the metering valve stem to closed position, a cover supported, manually operable device for shifting said element to tension its spring, a cover supported latch for said device, a resilient thermal element acting as a spring for the latch and disposed adjacent the burner and effective on reaching a predetermined temperature to release the latch and permit said element to close the metering valve.

4. The combination claimed in claim 3, wherein the cover carries a float lifter biased to lift the float and close the inlet valve when the manually operated device is unlatched and shifted to free the float when said device is latched.

5. In a portable, gravity fed, liquid fuel operated heater, a fuel supply tank, a float chamber, a fuel passage between the tank and chamber, a float valve in the chamber for controlling the flow of fuel into the chamber and maintaining a substantially constant level therein, a vaporizer below the chamber, a fuel passage between the chamber and vaporizer, a metering valve controlling flow from the float chamber to the vaporizer, a manually operable member biased to one position and latchable in another position, and devices operable by said manually operable member for closing both the metering valve and the float valve when the member is unlatched and releasing both valves when the member is latched whereby fuel may flow into and out of the chamber in accordance with the valve positions.

6. In a portable, gravity fed, liquid fuel operated heater, a fuel supply tank, a float chamber, a fuel passage between the tank and chamber, a float valve in the chamber for controlling flow of fuel into the chamber and maintaining a substantially constant level therein, a vaporizer below the chamber, a fuel passage between the chamber and vaporizer, a metering valve controlling flow from the float chamber to the vaporizer, a manually operable member biased to one position and latchable in another position, devices operable by said manually operable member for closing both the metering valve and the float valve when the member is unlatched and releasing both valves when the member is latched whereby fuel may flow into and out of the chamber in accordance with the valve positions, and a thermostat adjacent the burner and effective on reaching a predetermined temperature to release the latch.

7. The improvement in fuel flow regulation valves having a float chamber with an inlet and an outlet, a float controlled inlet valve, a metering valve controlling flow through the outlet and biased toward open position, which comprises a spring actuated inlet valve closer, a spring actuated metering valve closer, and a latchable de-

vice acting on both valve closers to stress the springs thereof so that the valves may open to allow flow of fluid and acting when unlatched to release both closers to stop flow and hold the mechanisms of both valves immobile.

8. In a device for regulating fluid flow from a chamber wherein it is maintained at a substantially constant level, an outlet passage having an upwardly facing valve seat, a vertically movable valve stem biased upwardly by a valve opening spring, a vertically movable member having a stop against which the spring urges the valve stem, a spring acting on the vertically movable member to urge it toward the valve stem and overpower the valve opening spring, a reciprocatory member having a cam which in one position lifts the vertically movable member and stresses the spring acting on the same, and a latch for securing the reciprocable member in the latter mentioned position, the said reciprocatory member on being unlatched shifting the cam to a position to release the vertically movable member to close the valve.

9. In a device for regulating fluid flow from a chamber wherein it is maintained at a substantially constant level, an outlet passage having an upwardly facing valve seat, a vertically movable valve stem biased upwardly by a valve opening spring, a cover through which the valve stem protrudes, a spring biased presser member pivoted on the cover and when released acting on the valve stem to move it to closed position, the presser member pivoted on the cover and carrying a stop which limits the opening movement of the valve stem, a cover supported oscillatory cam for lifting the presser member away from the valve stem so that the valve may open, and a cover supported latch for the cam.

10. In a fuel controlling valve, an upwardly opening chamber having a centrally disposed upwardly facing outlet valve seat, a cooperable outlet valve stem extending upwardly above the top of the chamber, a spring biasing the valve stem away from the seat, a cover for the chamber having an opening through which the valve stem protrudes, a fuel supply connection carried by the cover and leading to a downwardly facing inlet valve seat, an inlet valve stem movably carried by the cover, a float movably carried by the cover and when released cooperative with the inlet valve stem, an arm pivoted to the cover to move about a horizontal axis and biased downwardly against the outlet valve stem to move it to closed position, a float lifting spring carried by the cover which when released closes the inlet valve, and cover carried means for simultaneously releasing both the inlet and the outlet valve controls so that said valves may open or for simultaneously closing them so that fuel flow through each valve is prevented.

11. A valve such as claimed in claim 10, having a spring controlled latch for holding said means in valve opening position.

12. A valve such as claimed in claim 10, having a resilient bimetallic thermostat for holding said means in valve opening position and movable on heating of the thermostat to release said means.

13. A liquid flow regulating valve having a float chamber, a chamber cover having an inlet valve, a float in the chamber for controlling the opening and closing of the valve in accordance with fluid level, a float lifting spring carried in the float chamber and biased to lift the float and close the valve irrespective of liquid level, a plunger extending through the cover and engageable with

the spring to free the float, and a latched member for operating the plunger.

14. In a fuel flow regulating valve adapted for variable flow control by an extraneous operator, a valve stem biased toward open position, a presser member spring biased to act on the valve stem and move it to closed position, an actuator for the presser member spring biased to a position to free it from restraint by the presser member and manually operable to a position to move the presser member out of controlling relation with the valve stem, and a releasable latch to secure the actuator in the latter position so that the valve stem may be moved back and forth by the extraneous operator, the latch when released releasing the presser member to close the valve.

15. A valve such as claimed in claim 14, wherein in the presser member carries an adjustable stop which limits the opening movement of the valve stem.

16. The combination with a gravity fed liquid fuel burner having a vaporizing pot and an imperforate wall above the pot to provide a combustion chamber, of a safety control for the fuel supply thereof, comprising a valve through which fuel flows to the burner when the valve is open, valve opening means, latch controlled spring actuated valve closing means effective when unlatched to overpower the valve opening means and close the valve, a resilient bimetallic element holding the latch in latching position when cool, the bimetallic latch holding element being closely adjacent the combustion chamber wall so as to be subject to radiant heat therefrom, and forced draft producing means to supply air to the burner and arranged to blow cold air on to the bimetallic element to keep the element cool and in latching position, the bimetallic element being heated in the absence of the cold air to release the latch.

17. A forced draft operated liquid fuel burner having a vaporizer, means for supplying forced draft to the burner, a metering valve controlling the flow of liquid fuel to the vaporizer and having a stem biased toward open position, valve closing means, a releasable latch normally holding the valve closing means latched in position to free the stem of the metering valve so that it may open and acting on release to close the valve, and a thermostat connected to the latch to normally hold the latch closed, the thermostat being placed in a region adjacent the burner normally maintained cool by the forced draft but subject to radiant heat from the burner and undergoing such a rise in temperature when draft conditions for the burner are adversely affected as to bring about a release of the latch.

18. In combination, a liquid fuel burner which produces hot combustion products, a vertical tubular flue for the combustion products, a concentric down draft tube to supply air to the burner from below, means for supplying forced draft to the top of said down draft tube, a control valve biased toward open position for supplying fuel to the burner, valve closing means, means for latching the valve closing means in a position where it is ineffective to close the valve, and a bimetallic thermostat in the down draft tube and adjacent the flue so as to be subject to radiant heat therefrom, but being normally maintained cool by the air supplied through the draft tube, and thermostat operated means acting on the attainment of a predetermined higher temperature to release the latching means to unlatch the valve closing means.

19. In combination, a blower, a gravity fed, liquid fuel fired burner operated by forced draft from the blower and having a combustion chamber formed by a wall adapted to be heated by the burning fuel, means forming a down draft air passageway about the wall and normally cooled by the draft air, a hot air heater operatively connected with the combustion chamber and supplied with ventilating air by the blower, and means normally preventing overheating of the burner comprising a bimetallic thermostat in the air passageway and normally kept cool by the air therein, a fuel supply valve controlled by said thermostat, the thermostat being closely adjacent the combustion chamber wall so as to be subject to radiant heat therefrom and effective on overheating to close said valve.
